SUPPORT FOR EJECTOR CYLINDER

William P. Wohlford, Springfield, Ill., and Lester W. Taylor, Cedar Rapids, Iowa, assignors to Allis-Chalmers Manufacturing Company, Milwaukee, Wis.

Filed Sept. 28, 1965, Ser. No. 490,877
17 Claims. (Cl. 37—129)

ABSTRACT OF THE DISCLOSURE

A torsion bar suspension is provided for the open end of a scraper ejector cylinder to carry the weight thereof, thereby preventing damage and excessive wear of the rod gland and packing due to radial load thereon. The torsion bar suspension is vertically adjustable to compensate for manufacturing deviations and to facilitate assembly and disassembly.

It is a common practice to use a single stage hydraulic jack to move the ejector of an earthmover from its retracted position to its full eject position. The rear end of the cylinder is customarily pivotally connected to the forward side of the rear bumper and the piston rod is pivotally connected to the rear of the ejector. Since the ejector travels a considerable distance, an ejector jack must be provided which has a rather long stroke. Hence a single stage jack for such purpose, has a rather long cylinder and supplemental support therefor is desired to reduce the vertical load on the packing gland and rod packing, particularly when the rod is extended during ejection. Heretofore the rod end of the ejector cylinder has been supported on coil spring arrangements; however, such devices did not provide adequate position stability under rough operating conditions, did not provide precise positioning of the cylinder and was not conveniently adjustable.

It is an object of this invention to provide an improved ejector cylinder support which reduces vertical loading on the packing and packing gland yet accommodates small amounts of vertical swinging movement of the cylinder about its closed end pivot connection to the earthmover.

It is a further object of this invention to provide mechanism outlined in the previous object wherein the cylinder support acts to dampen vehicle induced movement of the cylinder.

It is a further object of this invention to provide a torsion bar suspension for an ejector cylinder which is adjustable to compensate for manufacturing and materials tolerances and to facilitate assembly and disassembly of the jack into and from the earthmover.

These and other objects and advantages will be apparent when the following description is read in conjunction with the drawings in which:

FIG. 1 is a side view of an earthmover incorporating this invention with parts broken away for illustration purposes;

FIG. 2 is a view taken along the line II—II in FIG. 1; and

FIG. 3 is an enlarged side view of the ejector cylinder support shown in FIG. 1.

Referring to drawings, the illustrated earthmover includes a scraper bowl frame structure 8 with side walls 9, 11. A draft frame 12 is pivotally connected to walls 9, 11, on a transverse pivot axis 13 so that the cutting edge

2

14 can be lowered to an excavating position by jacks 16, only one of which is shown. The earthmover also includes an apron 17 pivotally connected to the side walls 9, 11, on a transverse axis 18. The side walls 9, 11 are interconnected by a bottom wall 21 and a rear end frame 22 on which a pair of wheels 23 (only one shown) are mounted. The rear end frame 22 also includes a transverse bumper 24 and a longitudinal track 26 for rollers 27 on the rear end of ejector 28.

10 The ejector 28 is powered by a single stage double acting hydraulic jack 29 having its opposite ends pivotally connected to the ejector 28 and frame 22 by pins 31, 32, respectively. The pins 31, 32 pivotally connect the rod 36 and cylinder 33 to the ejector and frame structures at fixed 15 points thereon, respectively, and in a manner permitting the rod and cylinder to swing vertically relative to the structures if necessary during operation of the ejector. Inasmuch as the bumper 24 is reinforced to withstand pushing loads, the front side thereof provides a convenient 20 and structurally strong mounting point for the closed end of the cylinder structure 33 of ejector jack 29. When the jack 29 is expanded, the piston rod 36, piston 37 and ejector 28 move to the positions indicated by dot-dash lines 36', 37' and 28', respectively. In this full eject 25 position the material is ejected from the scraper bowl. It should be understood that the apron 17 is in its raised position during ejection. In the full eject or expanded position of jack 29, the weight of its components places considerably greater vertical loading on the rod packing gland 38 and packing 39. Further, the usual bouncing of the earthmover during unloading and immediately following unloading creates additional vertical loading on the rod packing gland and rod packing which tends to shorten the life of these components.

30 We conceived of providing the illustrated adjustable torsion bar suspension for the cylinder 33 to reduce the vertical loading on gland 38 and packing 39. The torsion bar suspension includes a transversely extending torsion bar 41 having its laterally opposite ends rigidly secured to the cylinder structure 33 through bracket portions 42, 43 welded to bar 41 and fastened to the cylinder 33 by cap screws 46, 47. The torsion bar has a longitudinally extending torque arm 48 welded thereto midway between its opposite ends which is pivotally connected at its free end to a vertically adjustable link in the form of a turnbuckle 49. The turnbuckle 49 and torque arm 48 are intersected by a vertical plane through the axis 61 of the jack 29. Pins 51, 52 pivotally connect oppositely threaded yokes 53, 54 of turnbuckle 49 to the free end of torque arm 48 and to frame structure 22. By turning the sleeve 56, the weight of the cylinder 33 may be removed from the rod 36. The proper adjustment of the turnbuckle 49 is achieved during installation of the jack 29 by connecting the closed end of the jack to frame 45 50 55 60 65 22 by pin 32, connecting the top of turnbuckle 49 to frame 22 by pins 52 and then adjusting the turnbuckle until openings in rod 36 and ejector 28 for pin 31 are in alignment to receive pin 31. Thus, the torsion bar support for the open end of cylinder 33 not only serves to reduce the vertical loading on packing gland 38 and packing 39, but the turnbuckle 49 facilitates installation of the jack 29 in the earthmover.

65 The usual tolerances permitted to provide economical manufacture are such that the longitudinal path followed by pivot pin 31, may not be a straight line continuation of axis 61 of jack 29 in its contracted condition. This being the case the torsion bar suspension permits the open end of the cylinder to move up or down to accom-

modate such nonlinear movement. Also during travel movement of the earthmover with the ejector jack extended, considerable dynamic forces act on the jack and particularly on the packing gland 38, packing 39 and piston 37. The torsion bar will resiliently twist to resist vehicle induced movement of the cylinder during earthmover operation and will restore the cylinder to its regular static position upon removal of the nonstatic forces.

From the foregoing it is apparent that an improved ejector cylinder support has been provided which resiliently permits slight vertical movement of the ejector cylinder and at the same time supports the cylinder sufficiently to reduce the vertical loading on the open end of the cylinder, the piston and the piston end of the rod. By making the torsion bar suspension vertically adjustable, a precise alignment of ejector jack components and pivot pins 31, 32 is readily obtained. For instance the turnbuckle 49 is properly adjusted if it removes the vertical load from pin 31 in the retracted condition of jack 29. In this condition the weight of the cylinder, rod and piston is supported by the torsion bar suspension and the rear pin 32.

The embodiments of the invention for which an exclusive property or privilege is claimed are defined as follows:

1. In combination with an earthmover having a frame structure and an ejector structure mounted in said frame structure for longitudinal reciprocal movement therein, the combination comprising:

a hydraulic ejector jack having a cylinder pivotally connected adjacent its closed end to one of said frame and ejector structures for vertical swinging movement relative thereto and a piston rod extending from the open end of said cylinder and connected to the other of said frame and ejector structures at a fixed point thereon, and
a torsion bar suspension interconnecting said one structure and said open end of said cylinder thereby providing resilient vertical support for the latter.

2. The mechanism set forth in claim 1 wherein said suspension includes means for selectively effecting vertical adjustment of said open end of said cylinder.

3. In an earthmover including a frame structure in which an ejector structure is reciprocated by a hydraulic jack having a cylinder pivotally connected adjacent its closed end to one of said frame and ejector structures for vertical swinging movement relative thereto and a piston rod extending from the open end of said cylinder and connected to the other of said frame and ejector structures at a fixed point thereon, the improvement comprising:

a torsion bar suspension providing resilient vertical support for the open end of said cylinder including
a torsion bar extending in a horizontal direction
and
means connecting portions of said bar spaced from one another in said horizontal direction to the open end of said cylinder and to said one structure, respectively.

4. The mechanism set forth in claim 3 wherein said means includes extensible and contractible mechanism for adjusting the vertical position of said open end of said cylinder.

5. In an earthmover including a frame structure in which an ejector structure is reciprocated by a longitudinally disposed hydraulic jack having a cylinder with its closed end pivotally connected to one of said frame and ejector structures for vertical swinging movement relative thereto and having a piston with a piston rod extending from the open end of said cylinder and connected to the other of said frame and ejector structures at a fixed point thereon, the improvement comprising:

a torsion bar suspension providing resilient vertical support for said open end of said cylinder including
a torsion bar having

a rod portion extending in a first horizontal direction, and

5 a torque arm portion extending from said rod portion in a second horizontal direction transverse to said first horizontal direction,

first means connecting one of said portions to said cylinder and

10 second means connecting the other of said portions to said one structure, said first and second means being spaced horizontally from one another in said first direction.

15 6. The mechanism set forth in claim 5 wherein one of said first and second means includes a vertically adjustable link.

7. The structure set forth in claim 6 wherein said one horizontal direction is transverse to the axis of said jack.

8. In an earthmover including a frame structure in which an ejector structure is reciprocated by a longitudinally disposed hydraulic jack having a longitudinally extending cylinder structure pivotally connected at a fixed point to one of said frame and ejector structures for vertical swinging movement relative thereto and a piston with, 20 a piston rod extending from the open end of said cylinder structure and connected to the other of said frame and ejector structures, the improvement comprising:

a horizontally disposed torsion bar extending transversely of the axis of said jack and having a torque arm extending from a central portion thereof in the longitudinal direction of said earthmover
means connecting opposite ends of said bar to any of said one and cylinder structures, and
means connecting the free end of said torque arm to the remaining of said one and cylinder structures.

25 9. The mechanism set forth in claim 8 wherein said means connecting the free end of said torque arm to said other structure includes a vertically adjustable link.

10. The mechanism set forth in claim 8 wherein said other structure is said frame structure.

40 11. The mechanism set forth in claim 10 wherein said means connecting the free end of said torque arm to said frame structure includes a vertically adjustable link.

12. The mechanism set forth in claim 8 wherein said torque arm lies in a vertical plane through the axis of 45 said jack.

13. The mechanism set forth in claim 12 wherein one of said connecting means includes adjusting means for selectively adjusting the vertical position of said open end of said cylinder.

50 14. The structure set forth in claim 13 wherein said other structure is said frame structure.

15. In an earthmover including a frame structure in which an ejector structure is reciprocated by a longitudinally disposed hydraulic jack having a cylinder structure pivotally connected at a fixed point to one of said frame and ejector structures for vertical swinging movement relative thereto and having a piston with a piston rod extending from the open end of said cylinder and 55 pivotally connected at a fixed point to the other of said frame and ejector structures, the improvement comprising:

65 a torsion bar suspension providing resilient vertical support for said open end of said cylinder including

a torsion bar extending in one horizontal direction and presenting a torque arm with a free end portion extending horizontally and transversely of said one horizontal direction and an attaching portion spaced horizontally from said torque arm,

70 first means connecting one of said portions to the open end of said cylinder,
second means connecting the other of said portions to said one structure.

16. The mechanism set forth in claim 15 wherein said torsion bar suspension includes vertical adjusting means for selectively positioning said open end of said cylinder in a vertical direction.

17. The mechanism set forth in claim 16 wherein said one horizontal direction is transverse to the axis of said jack.
